UNITED STATES PATENT OFFICE.

LEONARD GERHARDT, OF BALTIMORE, MARYLAND, ASSIGNOR TO TIN DECORATING COMPANY OF BALTIMORE, OF BALTIMORE, MARYLAND, A CORPORATION OF NEW JERSEY.

SHEET-METAL BOX.

Application filed March 15, 1919. Serial No. 282,895.

To all whom it may concern:

Be it known that I, LEONARD GERHARDT, a citizen of the United States, residing at Baltimore, State of Maryland, have invented new and useful Improvements in Sheet-Metal Boxes, of which the following is a specification.

This invention relates to boxes and the method of manufacturing the same, and has particular application to boxes made from tin and other sheet metals. In the present instance, I have, by way of illustration, shown my invention as embodied in the form of a box for containing candy, but I wish it to be understood that it is not of course limited to this particular purpose, as the box may be made as a receptacle for other commodities, especially those of a perishable nature liable to be affected by atmospheric conditions.

As is well known, it is the practice at the present day to pack confectionery and other food products in fancy boxes, and one popular style of box is that wherein both the cover and the body section are provided with continuous horizontally projecting flanges or edges having a characteristic appearance and known in the art and trade as "extension ledges" or "extension edges." Heretofore these boxes have been made from card-board, box-board and similar material, and although very neat, possess certain disadvantages, due to the inherent nature of the material used in their construction. For example, it is difficult to exclude air and moisture unless the box is wrapped in an outer covering of paper or the like, and furthermore, such boxes, owing to the fragile nature of the material used are liable to be crushed in transportation and in handling.

With my invention, however, I eliminate the disadvantages incident to the ordinary flanged card-board box and not only do I retain the attractive features of such neat box, but in addition thereto, my structure possesses important advantages. For instance, by making the box of sheet metal, such as tin, and by the method herein described, I provide a strong, durable, rigid container from which the air and moisture will be effectively excluded when the box is packed with the goods, thereby maintaining the lat-

ter fresh and in good condition. Furthermore, the box may be ornamented or lithographed with any desired design, or to suit the individual taste of the manufacturer or merchant, and will provide a strong, permanent and sanitary container.

Another object of my invention is the provision of a box made by such a method that the sheet metal used in its construction may be economically cut from large sheets, without undue wastage, and the parts constituting both the cover and the body portion of the box may be readily assembled. Inasmuch as both the cover and the body sections of the box are substantially duplicates, they may be made and assembled on the same machine, thus dispensing with the use of separate sets of machines for making the cover and the body.

With the above recited objects and others of a similar nature in view, my invention consists in the box and in the method of making the same set forth in and falling within the scope of the appended claims.

In Figures 1 to 7 inclusive, I have shown the various parts used in the manufacture of a shallow box, while in Figures 8 to 11 inclusive, I have shown the parts used in the construction of a relatively deep box, or one having the side walls thereof of substantially double the height illustrated by Figures 1 to 7 inclusive.

In the accompanying drawings,—

Figure 1 is a perspective view of a sheet metal blank used for making the top and bottom walls of the shallow box.

Figure 2 is a perspective view of the flanged strip which is to be formed to constitute the sides of the box.

Figure 3 is a perspective view of the blank shown in Figure 1, with three of the edge portions thereof rolled or folded inward to form flanges.

Figure 4 is a perspective view showing the strip of Figure 2 bent to form the four side walls of the box.

Figure 5 is a fragmentary perspective view, partly in section, and showing how the side walls are assembled on the flanged blank.

Figure 6 is a perspective view of the assembled side walls and bottom.

Figure 7 is a cross sectional view taken through the body of the box shown in Figure 6 and illustrating in dotted lines the cover of the box, this cover being substantially a duplicate of the body portion, but of slightly greater area.

Figure 8 is a perspective view of a strip used in making the body of the box as shown in Figure 9.

10 Figure 9 illustrates the body of a modified form of box.

Figure 10 is a cross sectional view through the body and cover of the modified form of box.

15 Figure 11 is a perspective view showing this modified form of box in its closed position, as when containing goods.

I will first describe the shallow form of box shown in Figures 1 to 7, and will subsequently describe the modified form, or 20 deep box, shown in Figures 8 to 11.

Referring to Figures 1 to 7 inclusive, the letter A indicates a blank of sheet metal, such as tin or the like, of approximately 25 rectangular form, with the exception that its corners are notched or cut away, as shown at 1. In the manufacture of a box of the kind herein shown, I use two of these blanks, one for the bottom and one 30 for the top. I then provide a strip, such as is shown at B in Figure 2, which is also made of sheet metal, such as tin, and this strip, when in flat form, is notched at intervals at one longitudinal edge portion, 35 as shown at 2, and this notched edge portion is then bent at right angles to the body of the strip to form the side flanges 3, and the end flanges 4 the strip being then bent into the form of an open frame. One end 40 of the strip is notched at one corner, as at 5, and bent into hook form, as indicated at 6. The other end of the strip is notched as at 7 and bent to form a hook, such as is shown at 8. The continuous, or unnotched 45 edge of the strip may then be rolled over inward, to form a beaded edge, indicated at 9. In making the box, the side edge portions of the blank A are first rolled or bent inward to form hook-shaped flanges shown 50 at 10, and then one end edge portion of the blank is likewise rolled inward to form the hook shaped flange 11. The strip shown in Figure 2 when it has been notched, beaded and flanged as described, is bent at the 55 notched portions into the form of an open frame to provide the two side walls 12 and the two end walls 13, with the hooked end 8 of the strip in engagement with the hooked end 6 to form the interlocking joint 14 at one corner. Thus the walls which are made 60 into a substantially continuous rectangular frame, constituting the side walls of the box, may now be slipped onto the flanged bottom shown in Figure 3 so that the side 65 wall flanges 3 will lie beneath the side

flanges 10 of the bottom, and so that one of the end wall flanges 4 will lie beneath the end flange 11. The end portion 11' of the bottom member may now be folded over the adjacent end wall flange 4 so that the body of the box will be completed, as is shown in Figure 6, that is to say, the extensions or flanges of the side walls will be completely covered by the inwardly bent flanges of the bottom and the side walls will be intimately and permanently united to the bottom to form the body of the box, which will appear as shown in Figure 6, and in cross section as shown in full lines in Figure 7. The same method is resorted to in 70 making the cover of the box which is shown in dotted lines in Figure 7 in position to be applied to the body of the box, the cover being indicated by the letter C. The cover is made of such dimension as to telescope 75 upon the body of the box, that is to say so that the depending walls of the cover will slip or fit easily yet snugly over the side walls of the body of the box so that the cover may be applied with facility and 80 pressed downward until its bottom edge contacts with the extension flanges of the body. Thus, the goods will be completely 85 enclosed in a double wall of metal, and an air-tight and moisture-proof structure will 90 be provided which will prevent deterioration 95 of the goods through atmospheric influences or other causes.

In Figures 8 to 11, I have shown the 100 modified form of box, which in many respects is similar to that illustrated by Figures 1 to 7 inclusive, only the side walls of the body are of double height when compared with the cover, and the body of this 105 box is provided with a median shoulder against which the bottom edge of the cover may rest. The cover of the box is shown at D and is made as heretofore described when referring to Figures 1 to 7. The body of this modified form of box is shown at E and the side walls thereof are made from a strip F, which is similar in many respects to the strip shown in Figure 2, except that it is relatively wide, for instance, twice the 110 width of the strip shown in Figure 2, and is formed with a median shoulder 15 so that when this strip is bent into rectangular form to form the two side and end walls of the body of the box, and is assembled on the bottom of the latter, the completed body portion will appear as shown at E in Figure 9. In assembling the cover upon the body of the box, the former is pressed down until its bottom edge rests against the shoulder 15, and the completely covered box will 115 appear as shown in Figure 11.

For the purpose of illustration and a clear understanding of the invention, I have shown a rectangular modified form of box, both in the preferred and modified form, 120

but I wish it to be understood that my invention is not limited to this particular form of box, as it may be made in other shapes, elliptical, circular and in any fancy shape 5 desired.

I am well aware that it is old in many box constructions to join the side walls to the bottom of the box by means of what is known in the art as a lock seam joint, and 10 my invention does not relate to the provision of mere lock seam joints in a box construction. The lock seam joints in box constructions have not the characteristic appearance of the type of construction to which my invention applies, my invention relating to 15 the provision of a metal box construction in which the flange joints between the bottom and side walls of the box provide what is known in the art and trade as "extension ledges" or "extension edges", these extension edges providing a peculiar and characteristic appearance well known in the trade. I desire it therefore to be understood that wherein in the following claims 20 I use the term "extension edge" or "extension ledge" I mean to designate that type of box flange which presents the characteristic appearance known to the trade as an extension ledge construction.

25 While I have herein shown and described certain embodiments of my invention, I wish it to be understood that I do not limit myself to all the precise details herein set forth by way of illustration, as modification 30 and variation may be made without departing from the spirit of the invention or exceeding the scope of the appended claims. For instance, the top wall of the cover instead of being flat, as shown herein, might 35 be slightly convex, or curved, to give it a rounded or "cushion" effect, which is incident to many of the boxes now on the market.

What I claim is:

40 1. An extension-edge sheet metal box comprising a body section and a cover section, the body section having a side wall portion and a bottom portion joined together by a flat multiply flange joint extending laterally of the side wall portion and lying substantially in the plane of the bottom portion and forming a continuous marginal flange at the bottom of the box; and the cover section including a top having a multiply flange extending therefrom and substantially in the plane of the said top, the multiply flanges of both sections lying in substantially parallel planes when the box is closed and extending laterally of the box body a substantial distance and forming characteristic "extension-edges" or "extension-ledges" therefor.

45 2. An extension-edge sheet metal box comprising a body section and a cover section, the body section having a side wall

portion and a bottom portion joined together by a flat multiply flange joint extending laterally of the side wall portion and lying substantially in the plane of the bottom portion and forming a continuous 70 marginal flange at the bottom of the box; and the cover section having a depending wall portion and a top portion joined together by a flat multiply flange joint extending laterally of the wall portion and 75 lying substantially in the plane of the top portion and forming a continuous marginal flange at the top of the box; the top and bottom marginal flanges extending from the box body a substantial distance and forming 80 characteristic "extension-edges" or "extension-ledges" therefor.

3. An extension-edge sheet metal box comprising a body and a cover, the said body comprising a bottom plate-like section having its edges inturned to provide a surrounding marginal flange and a vertical wall section made of a strip of metal bent in the form of an open frame and provided at its bottom with outwardly turned edge flanges 85 disposed in interlocking engagement with the inturned edges of the said plate-like section and forming therewith a substantially continuous flange joint at the bottom of the box; and the said cover comprising a top plate-like section having its edges inturned and a strip of metal provided at its top with outwardly turned edge flanges disposed in interlocking engagement with the inturned edges of the said top plate-like 90 section and forming therewith a flange joint at the top of the box, the said flange joints extending laterally of the box body a substantial distance and forming characteristic 95 "extension-edges" or "extension-ledges." 100

4. An extension-edge sheet metal box comprising a body and a cover, said body comprising a bottom plate-like section having its edges inturned to provide a surrounding marginal flange and a vertical wall section made of a strip of metal bent in the form of an open frame having its top edges inturned to form a marginal bead and provided at its bottom with outwardly turned edge flanges 110 disposed in interlocking engagement with the inturned edges of said plate-like section and forming therewith a substantially continuous flange joint in the plane of the said bottom section; and the said cover comprising a top plate-like section having its edges inturned and a strip of metal having its bottom edges inturned to provide a marginal bead and provided at its top with outwardly turned edge flanges disposed in interlocking engagement with the inturned edges of the said top plate-like section and forming therewith a flange joint lying in the plane of the top section, the said flange joints extending laterally of the box body a substantial distance and forming charac- 115 120 125 130

teristic "extension-edges" or "extension-edges."

5. An extension edge sheet metal box comprising a body and a cover, the said body comprising a bottom plate-like section having its edges inturned to provide a surrounding marginal flange and a vertical wall section made of a strip of metal bent in the form of an open frame and provided 10 at its bottom with outwardly turned edge flanges disposed in interlocking engagement with the inturned edges of the said plate-like section and forming therewith a substantially continuous flange joint at the bottom 15 of the box; and the said cover comprising a top plate-like section having its edges inturned and a strip of metal provided at its top with outwardly turned edge flanges disposed in interlocking engagement with 20 the inturned edges of the said top plate-like section and forming therewith a flange joint at the top of the box, the said cover strip having a telescopic connection with the vertical wall strip of the box body, the 25 said flange joints extending laterally of the box body a substantial distance and forming characteristic "extension-edges" or "extension-edges."

6. A two-part extension edge sheet metal 30 box comprising a body portion and a cover portion telescoping therewith, said portions being substantial duplicates one of the other, the body portion having a multiply flange extending laterally from the bottom 35 part thereof, the cover portion having a similar flange extending laterally from the top thereof, the multiply flanges of both portions lying in substantially parallel planes when the box is closed and extending a substantial distance from the box body and

forming characteristic "extension-edges" or "extension-edges" therefor.

7. A two-part extension-edge polygonal sheet metal box comprising a polygonal body portion and a cover portion, the body portion having a multiply flange extending therefrom and substantially in the plane of the bottom thereof, the cover portion including a top having a multiply flange extending therefrom and substantially in the 50 plane of the said top; the multiply flanges of both portions lying in substantially parallel planes when the box is closed and extending laterally of the box body a substantial distance and forming characteristic "extension-edges" or "extension-edges" 55 therefor.

8. An extension-edge sheet metal box comprising a body section and a cover section, the body section having a side wall portion and a bottom portion joined together by a flat multiply flange joint extending laterally of the side wall portion and lying substantially in the plane of the bottom portion and forming a continuous marginal flange at the bottom of the box; and the cover section including a top having its marginal edges inturned to form a multiply flange extending therefrom and substantially in the plane of the said top and also forming a continuous marginal flange, the continuous flanges of both sections lying in substantially parallel planes when the box is closed and extending laterally of the box body a substantial distance and forming characteristic "extension-edges" or "extension-edges" 70 therefor.

In testimony whereof I have hereunto set my hand.

LEONARD GERHARDT.
